DESIGN FOR A RANGE

Charles J. Kessler, Cleveland Heights, Ohio, assignor to Perfection Stove Company, Cleveland, Ohio, a corporation of Ohio

Application March 21, 1938, Serial No. 75,992

Term of patent 14 years

To all whom it may concern:

Be it known that I, Charles J. Kessler, a citizen of the United States, residing at Cleveland Heights, in the county of Cuyahoga and State of Ohio, have invented a new, original, and ornamental Design for Ranges, of which the following is a specification, reference being had to the accompanying drawing, forming part thereof, and wherein

Fig. 1 is a front elevation of a range showing my new design;

Fig. 2 is a left hand end elevation thereof, and Fig. 3 is a plan view.

The dominant or characteristic feature of the design resides in the portions shown in full lines.

I claim:

The ornamental design for a range, as shown and described.

CHARLES J. KESSLER.
